Primary Examiner — Mitchell I. Siegel*(74) Attorney, Agent, or Firm* — Schmeisser, Olsen & Watts LLP(57) **CLAIM**

The ornamental design for the lacrosse mesh with multiple mesh sizes, as shown and described.

DESCRIPTION

FIG. 1 is a front view of the lacrosse mesh with multiple mesh sizes;

FIG. 2 is another front view of the lacrosse mesh with multiple mesh sizes;

FIG. 3 is an enlarged fragmented front view of the lacrosse mesh with multiple mesh sizes taken from box 3 of FIG. 2; and,

FIG. 4 is an enlarged fragmented front view of the lacrosse mesh with multiple mesh sizes taken from box 4 of FIG. 2. The broken lines illustrate portions of a lacrosse mesh with multiple mesh sizes and form no part of the claimed design.

1 Claim, 4 Drawing Sheets**FIG. 1**

FIG. 2

FIG. 3
